UNITED STATES PATENT OFFICE.

JAMES E. JACKSON, OF LYNN, MASSACHUSETTS, ASSIGNOR TO UNITED SHOE MANUFACTURING CORPORATION, OF PATERSON, NEW JERSEY, A CORPORATION OF NEW JERSEY.

STOCK-FITTING MACHINE.

Application filed July 18, 1921. Serial No. 485,551.

This invention relates to stock-fitting machines, and is illustrated as embodied in a machine for channeling and grooving soles for McKay shoes.

5 A machine of this character is usually provided with an L-shaped channeling knife and the sole is commonly fed against the knife by means of a positively driven serrated feed wheel or roll arranged to engage the flesh side of the sole, and a smooth feed roll and a stationary presser foot arranged to engage the grain side of the sole in the vertical plane of the horizontal cutting edge of the knife. The stationary foot bears on the 10 sole with considerable force to insure proper cutting by the knife, and dragging the sole past such a foot requires a great deal of power.

An object of this invention is to lessen the 20 power required, and to eliminate the necessity for the smooth feed wheel, by substituting a roller presser foot for the stationary foot, by which arrangement the serrated feed wheel is sufficient to feed the sole, it being 25 opposed only by the knife and the slight rolling friction of the foot. Previous attempts to utilize a roller foot have been unsuccessful, because the roller could not be placed sufficiently close to the vertical plane 30 of the horizontal cutting edge of the knife, on account of the necessity of clearing the vertical edge of the knife, it being apparent that the diameter of even the smallest possible roll is sufficient to place the work-engaging portion of the roll too far ahead of 35 the knife when the roll has to clear the vertical portion of the knife.

This difficulty has been solved, in accordance with one feature of the present invention, by supporting a roller presser foot at one end only, and arranging an L-shaped channeling knife with its vertical cutting portion passing directly across the unsupported end of the roll, with the vertical cutting edge just behind the vertical diameter 40 of the roll, so that the work-engaging portion thereof bears the same relation to the horizontal cutting edge of the knife as does the stationary foot in the usual construction of the machine. If desired, an auxiliary presser member herein shown as a small stationary foot may be added to cooperate with the vertical portion of the knife, a comparatively light pressure being 45 required for holding the work against such

a vertical edge, and a foot of small size being sufficient. Thus the drag on the work by such a small stationary foot, at the relatively light pressure which is sufficient, is too small to detract materially from the benefit of the roller foot.

50 Soles are usually guided through stock-fitting machines of this character by the hand of an operator, and at a narrow part, such as a shank portion which projects beyond the serrated feed wheel, the sole is not so large but that the fingers of the operator sometimes engage the feed wheel. A further object of this invention, accordingly, is to avoid such annoyance by associating with 55 the feed wheel a safety guard which is arranged relatively to the outer side face and periphery of the feed wheel in a manner to prevent the operator's fingers from engaging the moving wheel. For convenience in carrying for the machine, I prefer to mount this 60 guard so that it may be swung back without removing it.

Further features of the invention are to be found in an improved guide to remove the 65 string of waste cut by the groover knife, an improved combination of stock-fitting tools and drive mechanism which permits either manual or variable-speed power drive, and in various combinations and specific 70 constructions which will be evident from the following description of the illustrative machine shown in the accompanying drawings, 75 in which

Fig. 1 is a front elevation, partly in section, of the machine;

Fig. 2 is a perspective of the tool-carrying head, showing part of the feed-wheel and its associated safety guard;

Fig. 3 shows the relative positions of feed 80 wheel, roller foot, channel knife, and groover 85 knife in operating on a sole;

Fig. 4 is an exploded perspective view 90 showing the means for adjusting the roller 95 foot;

Fig. 5 is a side elevation of the roller foot; 100 and

Fig. 6 is a view of the actuating lever for the clutch.

The machine which has been selected for 105 illustrative purposes in describing the invention is a stock-fitting machine of the type known as a McKay channeler. It is a bench machine, comprising generally a base 10, upon which is supported a frame 12, in 110

which is journaled a power shaft 14 and also a feed-wheel shaft 16 driven from shaft 14 by gears 18. A serrated feed-wheel 20 is removably mounted on one end of shaft 16 by means of a suitable screw threaded into the end of the shaft, and carries a bevel gear surface which drives an edge gage 22. The edge gage is carried on a spring-pressed slide which can be withdrawn by rocking bell crank 24 by operating a treadle rod 26. The channel and groover knives are carried by a head 28 pivotally mounted on frame 12 at 30, which may be lifted by a second treadle-rod (not shown) which rocks a bell crank lever 31 against spring 32. A set screw 33 is provided to limit the downward movement of the head 28. As these parts are all well known to those skilled in the art, no further description of them is considered necessary.

In order to secure the advantages of both hand operation and a variable-speed power drive, there is provided an improved stopping and starting mechanism comprising a hand wheel 40 keyed to shaft 14, and a belt pulley 42 loosely mounted thereon. A spring 44 constantly urges the hand-wheel and the pulley apart, to permit manual operation. To permit of variable-speed power operation, the pulley 42 may be pressed with greater or less force into frictional engagement with the hand wheel 40 by operation of a wedge 46 by means of a lever 48 (or spring-pressed treadle rod 50 actuated by a suitable treadle, not shown). The wedge 46 co-operates with a second wedge 52, which is prevented from turning by an extension 54 which engages the lower portion of the wedge 46.

Lever 48 is pivoted on the frame 12 at 56 and may extend below the pivot to carry a brake-shoe 58, which engages the rim of hand wheel 40 to prevent over-running when the clutch is thrown out for manual operation.

In order to protect the fingers of the operator, there is provided a novel safety guard consisting of a support 60, secured to the frame at 62, and a guard member 64 mounted thereon by means of a hinge 66. The guard member 64 is located opposite the outer side face of the feed wheel and is formed with a curved outer margin concentric with the periphery of the feed wheel and arranged closely adjacent to said periphery. A torsion spring 68 urges member 64 into active position beside the feed wheel 20, while yet permitting it to be swung back out of the way so that it will not interfere with the removal of the feed wheel 20.

As is usual in McKay channeling machines, the channel knife 70 is mounted for adjustment in the head 28 on a slide 72 which can be moved vertically by turning

an adjusting screw 74, and the groover knife 76 is mounted on a second slide 78 which can be adjusted vertically by turning an adjusting screw 80. The groover knife may be lifted from the work independently of the channel knife, for channeling about the toe, by raising the slide 78 against a coil spring 82 by a treadle-controlled lever 84, the connections from the lever passing through a slot 85 in the side plate 86 of head 28, as is well-known to those skilled in the art.

As explained above, an improved groover string guide or remover 87 directs the string of waste removed by the groover knife. This guide is secured to the slide 78 by a screw 88, so that it may be placed on existing machines without changing them otherwise if desired. The screw 88 passes through an outer plate or support, and then through a vertical slot 91 in the upper portion of the string guide, so that the guide may be moved vertically or angularly, and held in adjusted position by tightening the screw 88. The string guide 87 is made up of an upper plate-like portion, containing the slot above referred to, and a lower or guide portion, pivoted together at 93 so that the lower portion may be swung toward and from the groover knife by an adjusting screw 89 which engages the lower portion of the guide at a point below the pivot 93. The improved guide is open at the top and is of relatively large cross-section, so that it does not readily become clogged. As it is mounted on the slide which carries the groover knife, it accompanies that knife when it is raised and lowered.

The head 28 is formed with an extension 90 upon which is adjustably mounted a novel roller presser foot 92, which holds the work down while the channel is being cut. Heretofore it has been necessary to use a stationary presser foot on McKay channeling machines because of the seeming impossibility of mounting a roller foot close enough to the vertical shank portion of the commonly used L-shaped knife such as shown at 70 in Fig. 3. According to the present invention, the vertical shank portion of the knife passes across the end of the roller foot, so that the cutting edge of the horizontal portion of the knife comes just behind the vertical plane passing through the axis of 115 the roller foot, thus securing the same efficient relation of parts as with a stationary foot. Since the vertical shank portion of the knife 70 is beveled, as shown in Fig. 3, to produce its vertical cutting edge, the thickness of the stock in this portion of the knife may prevent the roller presser foot from being located as close to the vertical cutting edge as is desirable to insure clean and accurate cutting and accordingly an auxiliary presser member, herein shown as a

small stationary presser foot 94 (Figs. 4 and 5), is arranged to cross the end of the roller foot 92 to co-operate with the vertical portion of knife 70. This arrangement will 5 be apparent from a comparison of Figs. 3 and 4.

The stationary auxiliary presser member or foot 94 is adjustably secured to a plate 96 by screws 98, and the roller foot 92 is 10 mounted on plate 96 by a small spindle projecting therefrom. The roller foot is supported when pressed against the work by a small anti-friction roll 100 carried by the plate 96. The plate 96 is arranged for 15 horizontal adjustment on a plate 102, which in turn is mounted for vertical adjustment on an extension 90, screws 104 serving to move the plates to make necessary adjustments, and a clamp screw 106 serving to 20 clamp them in adjusted position.

The operation of the machine will be apparent from the foregoing description. When a sole is to be channelled, the bell crank 31 is rocked by its treadle to raise the head 25 28, and the sole is inserted. The lever 48 is depressed, either by hand or by means of its treadle, and the sole is fed forward. As the toe is approached, if the toe is to be nailed as is usual with pointed McKay 30 shoes, the groover knife is raised by actuating the treadle-controlled lever 84 to raise the slide 78, and when the bend at the toe is reached, the lever 48 is released and the hand-wheel 40 is operated to turn the toe. 35 After passing the toe, the lever 48 is again operated, and the groover knife is lowered at the proper point. The head 28 may be raised to withdraw the sole when it is finished, or the knives may simply be allowed 40 to run out at the end of the sole.

While my invention has been illustrated and described as embodied in a particular type of stock-fitting machine, it is not the intention to limit its scope thereby, or otherwise than by the terms of the appended 45 claims.

Having described my invention, what I claim as new and desire to secure by Letters Patent of the United States is:

50 1. A machine for channeling soles comprising, in combination, an L-shaped channel knife having a horizontal portion to provide a horizontal cutting edge and a vertical portion to provide a vertical cutting edge, a sole-supporting feed wheel, a roller presser foot arranged with the vertical plane through its axis in close proximity to the horizontal cutting edge of the knife and with one end face opposed to the side of the 55 vertical portion of the knife, a spindle carrying the roller presser foot, and means for supporting said spindle only at the end of the foot opposite from the vertical portion of the knife.

65 2. A channeling machine as defined by

claim 1, in combination with an auxiliary presser foot at the end of the roller foot and co-operating with the vertical cutting edge of the channel knife.

3. A machine for channeling McKay soles 70 comprising, in combination, a sole-supporting feed wheel, a roller presser foot for engaging a sole supported by the feed wheel, an L-shaped channel knife having a horizontal portion extending beneath the roller 75 foot shaped to provide a horizontal cutting edge approximately in the vertical plane through the axis of the roller foot and a vertical portion extending across one end of the roller foot shaped to provide a vertical 80 cutting edge in the vertical plane through the horizontal cutting edge, and a roll arranged to engage the periphery of the roller foot to support the roller foot when the latter is pressed against the work. 85

4. A stock-fitting machine comprising, in combination, a sole support, a roller presser foot for engaging a sole on the support, a channel knife having a cutting edge extending beyond one end of the roller foot, and 90 an auxiliary presser member for engaging the work in line with said extension of the cutting edge.

5. A stock-fitting machine comprising, in combination, a tool to operate on work 95 guided by the hand of an operator, a serrated, positively rotated work supporting feed wheel, and a safety guard located opposite the outer side face of the feed wheel and having a curved outer margin concentric with the periphery of the feed wheel and arranged closely adjacent to said periphery. 100

6. A stock-fitting machine comprising, in combination, a tool to operate on work 105 guided by the hand of an operator, a serrated, positively-rotated work supporting feed wheel, a frame for the machine, and a safety guard consisting of a part fastened to the frame, a second part hinged thereto at right angles to extend across the side of the feed wheel to prevent the fingers of the operator from coming into engagement therewith, and a spring holding the second 110 part in operative position while permitting it to be swung back. 115

7. For use in a McKay sole channeling machine which has a groover knife, a spring-pressed slide for the knife, a manually-controlled lever, a connection between the lever and said slide for raising the knife, a device for guiding and removing the string of waste cut by the groover knife comprising a support portion to extend upwardly and be mounted on the connection between the lever and the slide, and a guide portion pivoted to the support portion for adjustment toward and from the groover knife, 120 said guide portion extending downwardly and forwardly to receive the string of waste 125 130

as it is cut, and means for varying the adjustment of said guide portion.

8. A stock-fitting machine comprising, in combination, a tool for operating progressively on a piece of work, a feed wheel to feed work guided by the left hand of an operator thereto, a rotary shaft parallel to the axis of the feed wheel and arranged to drive the wheel, a hand wheel immovably mounted on the shaft for manual operation of the machine by the right hand of an operator engaged in feeding the work with his left hand, a belt pulley loosely mounted on the shaft beside the hand wheel, a wedge 10 15 20 25 30 35 40 45 50 55 60 65 70 75 80 85 90 95 100 105 110 115 120 125 130 135 140
